Attorneys.

UNITED STATES PATENT OFFICE

IRVING WARNER, OF WILMINGTON, DELAWARE

SHIPPING CONTAINER

Application filed April 17, 1929. Serial No. 355,768.

This invention relates to shipping containers, especially to containers of the mailing tube type. More particularly, it relates to a container of the character described 5 which may be repeatedly sent back and forth between two senders.

It is sometimes necessary that an article of merchandise or certain business papers or drawings be repeatedly sent back and forth 10 between two senders. For example, a fountain pen may be sent to a purchaser by the manufacturer, and the purchaser may later send the pen back for repairs. After the 15 repairs are made, the pen is returned to the purchaser. This sending and returning may occur many times.

It is an object of this invention to provide a tubular container designed to facilitate the handling of merchandise, papers, etc., 20 repeatedly transmitted between two senders, by having permanently secured to the mailing tube two separate addresses with a movable member adapted to cover one of said addresses, alternatively and selectively.

Another object of the invention is to provide a mailing tube having two complete address labels thereon, each label bearing the name, etc., of an addressee and of a sender, 25 the names being reversed on the two labels so that the sender on one label appears as addressee on the other, with readily adjustable means to expose one only of the two labels.

These and further objects will appear from 30 the following description taken in connection with the accompanying drawing wherein:

Fig. 1 is a perspective view of a cylindrical container embodying the invention;

Fig. 2 is a side elevation thereof with the 35 seal partly broken away, and

Fig. 3 is an elevation of a modified form with the shield partly broken away.

A tubular container 1 is shown as of the 40 mailing tube type and comprises two telescoping sections meeting along a central line 2, the surfaces of the sections being flush. Although I have illustrated a cylindrical container, it will be understood that it may be 45 oval or polygonal in cross-section.

Permanently secured to the tube 1 and each 50

occupying approximately half the length of the tube are two address labels 3 and 4. These labels 3 and 4 have the same names and addresses thereon, the names and addresses being reversed however as regards sender and 55 addressee. As seen in Fig. 1, label 3 indicates that the container is being sent to the Roe Pen Corporation, 154 School St., Boston, Mass. by John Doe, 25 Blank St., New York, N. Y. On label 4, however, the container is 60 addressed to John Doe and is being sent by the Roe Pen Corporation.

In order that only one of labels 3 and 4 may be exposed, a slideable shield 5 is provided. The shield 5 consists of a cardboard or other 65 suitable tube slightly larger in diameter than the container 1 and of corresponding cross-section, and having a sliding fit thereon. Shield 5 is approximately half the length of tube 1 so that it covers up one of the labels 3 70 and 4 and leaves the other exposed.

In order that shield 5 may not be slid completely off tube 1, end flanges 6 and 7 may be provided on tube 1, these flanges projecting 75 outwardly, as seen.

The shield 5 is adapted to be secured in either of its two positions by the postage stamps when the tube is mailed, or by gummed paper 8, as seen in Fig. 2, or by a 80 rubber band, or any other appropriate means.

It is believed that the operation is obvious. When the container is to be sent to the Roe Pen Corporation, John Doe would simply slide the shield 5 to the position shown in Fig. 1 and secure it by stamps, gummed paper or otherwise. When the container is to be returned to John Doe, the Roe Pen Corporation would slide the shield 5 to the other end of the container, secure it there, and forward the tube. It will thus be apparent that the 85 shipping of small articles, papers, etc., is greatly facilitated by the use of the invention described.

In the modification shown in Fig. 3, the address label 3' is turned upside down as regards label 4' so that the return label will 90 always appear at the left hand end of the container.

Although the labels 3 and 4 and shield 5 95 have been shown as occupying about half the

length of the container, it will be obvious that they may be much smaller, the only essential being that the shield 5 be of sufficient length to cover one complete label. It will also be obvious that the particular type of mailing tube is immaterial since one with a removable end, or any other type, could be used.

Obviously too, the addresses may be printed 10 or otherwise applied directly to the container, instead of employing labels pasted to the same.

These and various other modifications may be made without departing from my invention 15 as expressed in the accompanying claims.

I claim:

1. A shipping container having a plurality of complete shipping addresses thereon, and a shield slidably movable on said shipping 20 container for completely covering one or the other of said shipping addresses, selectively, while leaving the other entirely exposed.

2. The structure as in claim 1 wherein means is provided for temporarily securing 25 said shield in position.

3. A shipping container comprising a cylindrical tube, a plurality of shipping addresses thereon, and a cylindrical shield closely surrounding and slidable on said shipping 30 container for selectively covering one or the other of said shipping addresses.

4. The structure as in claim 3 wherein said shipping container has means adjacent each end thereof to prevent said shield from being 35 slid completely off said container.

In testimony whereof, I affix my signature.
IRVING WARNER.
